C. H. SMITH.
Latch.

No. 225,728.

Patented Mar. 23, 1880.

INVENTOR.

Charles H. Smith

UNITED STATES PATENT OFFICE.

CHARLES H. SMITH, OF NEW BRITAIN, CONNECTICUT, ASSIGNOR TO THE RUSSELL & ERWIN MANUFACTURING COMPANY, OF SAME PLACE.

LATCH.

SPECIFICATION forming part of Letters Patent No. 225,728, dated March 23, 1880.

Application filed December 10, 1879.

To all whom it may concern:

Be it known that I, CHARLES H. SMITH, of New Britain, in the county of Hartford and State of Connecticut, have invented a new and useful Improvement in Door-Latches; and I do hereby declare that the following specification, taken in connection with the accompanying drawings, forming a part of the same, is a full, clear, and exact description thereof.

10 My invention relates to that class of door-latches known as "anti-friction latches," in which a lever is employed having a salient face which projects beyond the face-plate of the latch, and the office of which is to diminish the friction incident to the working of the latch.

15 In latches of this character as usually heretofore constructed this lever has been pivoted to or otherwise directly connected with the latch-bolt, so that the inward and outward movements of said bolt have been directly produced by the movements of said lever.

20 The present improvement consists in the combination of a lever having a face projecting beyond the face of the door-latch and turned on its pivot by contact with the face of the striker-plate with the mainspring, which operates to project the latch forward into the mortise in the door-jamb, so that when the 25 door is closing the resistance of such mainspring to the sliding of the bolt backward into the latch-case will be taken off the latch-bolt; and the invention also consists in the combination, with the sliding latch-bolt, of a spring, 30 the office of which is to act, so soon as the resistance of the mainspring is taken off, to retract the latch-bolt.

35 Referring to the drawings, Figure 1 represents, in side elevation, a latch embodying my improvement, with the cap-plate removed and the bolt in its projected position. Fig. 2 shows a longitudinal section of the latch on line xx of Fig. 1; and Fig. 3 represents, in perspective, the salient-faced lever, the auxiliary lever engaging it, and the operative spring. Fig. 4 represents, in side elevation, the front portion of the latch shown in Fig. 1 having the operative spring of such proportions and so bent as to render the presence of the auxiliary lever unnecessary.

A is the latch-case, and a the face-plate thereof, which plate is mortised to receive the head b of the bolt B and the salient-faced lever C. This lever is pivoted to the face-plate of the latch, and is provided with a slot, c , as shown in Fig. 3, which slot is occupied by the end of an auxiliary lever, D, mounted upon a stud, E, projecting from the latch-case. Mounted upon the same stud is the main-spring F, one of whose ends engages a lug, d , 55 upon the lever D, the other end engaging a stud, e , upon the case. Practically, the lever D is a part of the mainspring, as is fully illustrated in Fig. 4, wherein the lower arm of the spring F is longer than when used with said lever D, and is extended across the line of the bolt B into the slot c of the salient-faced lever C. It has the same contact with the bolt and the salient-faced lever that the lever D has, and operates precisely like the shorter spring 60 shown in the other figures, because the lever D operates as a mere extension of the lower spring-arm.

The spring F operates through the lever D to keep the lever C projected beyond the plane 75 of the face-plate a , and also causes the lever D to engage the rear of the bolt-head b , as shown in Figs. 1 and 2. The lever D, connected with or forming a member of the spring F, therefore serves to keep the latch-bolt B projected, 80 and also, by its reaction, operates to shoot the bolt outward from the latch-case after it has been retracted. In short, if the lever C were removed from combination with the main-spring and the latch-case, the construction remaining would be substantially that of an ordinary door-latch. For drawing in the latch-bolt there are the usual knob-spindle levers 85 G G', which operate upon the said bolt in a well-understood manner.

90 It will be observed that the latch-bolt B is furnished with a spiral spring, H, Fig. 2. The office of this spring, which is under tension when the latch-head projects beyond the face-plate, is to shoot the bolt into the latch-case 95 so soon as the superior force of the main-spring, exerted in the opposite direction, is taken off. One end of the spring H engages a stud, K, upon the latch-case, while the other end of said spring bears against a depending 100

stud, B', upon the bolt B. The force of this spring H is less than that of the spring F, so that when the bolt B is in its normal position it is projected, as shown in Figs. 1 and 2. When, however, the resistance offered by the mainspring F to the rearward movement of the bolt is removed by the action of the lever C, as the result of its face coming into contact with the door-jamb, and of the combination of such lever with the mainspring, the full force of the spring H operates to retreat and house the bolt.

The operation of the latch is as follows: When the door is closing the salient face of the lever C comes into contact with the door-jamb and swings the lever D backward, and the bolt B is retracted by the spring H until the door is fully closed, and the bolt-head b and lever C pass into alignment with the mortises or openings in the striker-plate. When the door-jamb no longer furnishes a resistance to the force of the spring F the said spring reacts and, through the lever D, projects the bolt and lever C into the striker-plate mortises, and the door is held fast. In opening the door the knob-levers G G' draw back the bolt in the usual manner when the knob is turned, and the lever D is moved backward in readiness to project the bolt B and lever C into their normal positions when the knob is released.

Although, as above specified, and shown in

the drawings, I have provided the latch with the spring H to retract the bolt, yet the said spring may be dispensed with, since, upon the lever D being moved backward by the contact of the lever C with the door-jamb, no obstruction would be presented to the retreat of the bolt B within its case, and said retreat would be produced by the contact of the face of the bolt-head with the striker-plate, and the bolt would afterward be projected into its normal position when the lever D was allowed to move, as above described. It is preferable, however, to employ the spring H.

Having described my invention, what I claim, and desire to secure by Letters Patent, is—

1. The combination, substantially as herein described, of the lever C, hinged to the latch-case, with the mainspring of the latch-bolt for taking off the resistance of the spring to the backward movement of the bolt when the door is closing.

2. The combination of the lever C, hinged to the latch-case, the mainspring of the latch-bolt, the latch-bolt, and a retracting-spring to shoot the bolt into the case when the resistance of the mainspring is taken off, substantially as described.

CHARLES H. SMITH.
